CLAIM

The ornamental design for a user interface for a computer display, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

Applicants claim priority under 35 U.S.C. § 120 to U.S. patent application Ser. No. 29/213,920, filed on Sep. 27, 2004, which claims priority to U.S. patent application Ser. No. 29/155,482, filed on Feb. 13, 2002, now U.S. Pat. No. D499,112, and which claims priority to U.S. patent application Ser. No. 29/116,440, filed on Jan. 4, 2000, now U.S. Pat. No. D469,957.

The file of this patent contains at least one drawing executed in color. Copies of this patent with color drawing(s) will be provided by the Patent and Trademark Office upon request and payment of the necessary fee.

The sole FIGURE is a front view of a user interface for a computer display showing our new design.

The broken line showing of the computer display, window, and the shape surrounding the image forms no part of the claimed design.
